DESIGN FOR A QUILT

Julius Davis; New York, N. Y.

Application May 11, 1938, Serial No. 77,122

Term of patent 7 years

To all whom it may concern:

Be it known that I, Julius Davis, a citizen of the United States, residing in New York city, in the county of New York and State of New York, have invented a new, original, and ornamental Design for a Quilt, of which the following is a specification, reference being had to the accompanying drawing, forming part thereof.

Figure 1 represents a top plan view of the quilt embodying the design;

Figure 2 is an end elevational view of the quilt embodying the design.

The characteristic feature of the design is the

arrangement of a prominently checkered quilt having a network of generally equally spaced crisscrossed lines extending diagonally across the face of said quilt in angular relation to the lines forming the outlines of the checks thereof, and a generally continuous border of substantial width extending along two opposite edges of said quilt.

I claim:

The ornamental design for a quilt, as shown and described.

JULIUS DAVIS.
